Pelatiah M. Hutton of Rensselaer, N.Y.
Letters Patent No. 407. Dated Sept 2^d, 1851.

The Schedule referred to in these Letters Patent and making part of the same.

To all whom it may concern. Be it known that I, Pelatiah M. Hutton, of the city Troy, County of Rensselaer & State of New York, has invented or produced a new and original design, ornament or impression to be cast upon cast-iron bedsteads and I do declare that the following is a full & exact description of the same.

In the annexed drawing A & B, are the head and foot boards, being of different heights each of which with legs sustaining it is one piece. C & D, are the connecting side pieces being of different lengths each of which is also one piece.

The head boards & foot boards are unlike as are the side pieces and can be so changed as to give three different heights of head and foot board and two different lengths. These four pieces are the only ornamental work in

the bedsteads and they are ornamented with curved lines regular & irregular, as seen in the drawing.

What I claim as my invention & desire to secure by letters Patent is the designs & ornaments upon the parts A B C & D, combined as in the drawing hereunto annexed, as applied to Iron bedsteads.

Dated Troy, June 2^d 1857.
